CLAIM

The ornamental design for an ironing board storage compartment, as shown and described.

DESCRIPTION

FIG. 1 is a front perspective view of the ironing board storage compartment showing my new design.

FIG. 2 is a back perspective view thereof.

FIG. 3 is a front view thereof.

FIG. 4 is a back view thereof.

FIG. 5 is a side view thereof.

FIG. 6 is another side view thereof.

FIG. 7 is a top view thereof.

FIG. 8 is a bottom view thereof; and,

FIG. 9 is a bottom perspective view of the ironing board storage compartment showing the ironing board stand extended.

The broken line disclosure of the ironing board stand illustrates the environment. The remaining broken lines illustrate portions of the ironing board storage compartment. The broken line disclosures form no part of the claimed design.

1 Claim, 9 Drawing Sheets
